UNITED STATES PATENT OFFICE

FELIX WOLF, OF VIENNA, AUSTRIA
MANUFACTURE OF GLACÉ FABRICS

Application filed April 7, 1926, Serial No. 100,360, and in Austria August 1, 1925.

My invention relates to a method of and means for producing glossy or lustrous fabrics as a substitute for glacé-thread fabrics or fabrics of polished yarn.

5 The warp-threads of the known glacé-thread fabrics, which are employed as linings as well as for other purposes, consist of glacé-threads which are produced in the following manner:

10 The raw yarn is reeled on two-lease reels. Hereafter the same is dyed and dressed and made glossy or lustrous by means of rotating brushes. The threads are then reeled and warped and the warp is finished in a known 15 manner. It is obvious that this procedure is very cumbersome and expensive and calls for a number of special machines.

According to my invention fabrics are produced which are a satisfactory substitute 20 for glacé-thread fabrics, but which are produced in a more simple and less expensive manner. The finished fabric is soaked with a dressing means and subsequently the fabric under tension is treated on one side or on both 25 sides by means of rapidly operating lustring or polishing tools, particularly brushes, until the material shows the character of a glacé-thread fabric. The fabric to be treated in this manner may be manufactured either of 30 coloured yarns or it can be dyed as a whole before the lustring or polishing is done.

Thus according to the new method all special working operations for producing the glacé-thread are dispensed with. The manufacture of the lustrous fabric which is a satisfactory substitute for the known glacé-thread fabrics, because only a simple subsequent treatment of a finished fabric is necessary to be carried out, which is far more simple than the particular process above referred to and which is necessary for producing glacé-threads and warps thereof.

Polishing of the finished fabric is preferably performed by means of brush-rollers, 45 which are arranged transversely to the longitudinal direction of the fabric, the latter under tension being pulled over the brush-rollers in a longitudinal direction. Thus the brush-rollers rotate in the direction of the movement of the fabric in such a manner that

the circumferential speed of the brush-rollers at the contacting places is multiplied a number of times more than the speed by which the fabric is drawn past the brushes. However it is also possible to allow the brushes to 55 rotate in the opposite direction.

In order to produce the lustre on the fabric it is necessary to first glue the fibres of the threads, which the fabric consists of, to the threads themselves, this being accomplished 60 by submitting the fabric soaked with a sticky dressing means to a brushing action. Then the fabric has again to be treated with brushes in order to produce the highly lustrous surface, the gluing of the fibres serving only 65 to smooth the surface of the fabric, thus preparing it for the subsequent lustring.

The lustre itself can be produced only by submitting the fabric to an intensive brushing for a suitably long time, and if it is desired to continuously move the fabric over the 70 rotating brushes in order to obtain a continuous process, a considerable number of such rotating brushes is necessary.

One mode of carrying out my invention is 75 illustrated by way of example in the accompanying drawings in which

Figure 1 shows in elevation and

Figure 2 in plan view a machine constructed according to the invention.

At one end of a frame 1 is mounted a beam 2 from which the fabric 3 is wound off, and at the other end of the frame 1 is located a beam 4 on which the fabric is wound up after having travelled through the machine. The 85 beam 4 is driven by means of a chain 5, which passes over a chain-wheel 6, mounted on a shaft 7. The latter carries a worm-wheel 8, which is driven by a worm 9, the latter being mounted on a shaft 10 driven by a shaft 12 90 by means of a belt 11.

The frame 1 carries further a number of guide-rollers 13, a trough 15 which contains the dressing liquid which for example may be composed of the following proportions of quantities, 80 l. of water, 10 kg. of wheat starch, 1/2 kg. of paraffin, 1/2 l. of Turkey red oil, 1/2 l. of glycerine, and a roller 16, between which and a roller 17, arranged above the roller 16, 100 pass the fabric 3 after having been wound off

the beam 2 and having passed the guide-roller 13, whereby the dressing liquid is taken up by the surface of the roller 16 and transmitted to the fabric. The upper roller is influenced by a loaded lever 18 in order to press the fabric 3 against the roller 16.

The fabric 3 passes then over a guide-roller 19 and enters that part of the machine where the lustring or glazing of the fabric is performed by means of rotating brushes. In this part of the machine guide-rollers 20 are mounted in the frame 1 in such a manner that the fabric 3 passes in zigzag over these rollers and moreover a number of brush-rollers 21 is arranged one after the other in such a manner as to allow the fabric to come into contact with each brush-roller, in two places. But it may also be that the brush-rollers are so arranged as to come into contact with the fabric only in one place.

The guide-rollers 20 may be adjustably mounted in a vertical direction as illustrated for the rollers 20 shown in Figure 1 at the left end of the lustring portion. The bearings of these rollers 20 may be adjusted in a vertical direction in their supports 24 and 25 respectively by means of vertical screws 22, in order to vary the tension of the fabric as required. Adjusting and tentering devices of this kind may be provided for all the guide-rollers 20 or for some rollers only.

After leaving the last guide-roller 20, the fabric 3 passes over resistance-rollers 26, 27 and 28, the roller 27 being mounted on the shaft 7, which as above mentioned is driven by the worm-wheel 9. From here the fabric 3 proceeds to a drying-box 29 where it passes over and down over rollers 30, 31, 32, 33 and 34 in order to travel for a considerable time through the drying box. A coil-pipe 35 is arranged in the lower part of the drying box and is supplied with steam by means of a tube 36, whereby the interior of the drying box 29 is heated and the fabric is completely dried. The vapours escaping from the fabric leave the drying box through a chimney 37.

From the drying box the fabric 3 passes over a guide-roller 38 to the beam 4, where it is wound up.

The roller 16 of the dressing trough 15 is mounted on a shaft 39 carrying a worm-wheel 40 which is driven by a worm 41, arranged on the shaft 10, which carries also the worm 9. Therefore the roller 16 of the dressing trough is driven in accordance with the guide-roller 27 as well as with the beam 4, whereby the required tentering condition of the fabric 3 is secured, during the whole travel through the machine.

The brush-rollers 21 are driven in groups by shafts 42 and 43, these again being driven by a motor which drives also the shaft 12.

By passing between the rollers 16 and 17 the fabric is soaked with the dressing liquid and immediately afterwards is subjected to

the action of the brush-rollers. In consequence of their high speed of rotation, these brush-rollers intensively act upon the continuously travelling fabric in such a manner that not only the dressing liquid is uniformly distributed over the surface of the fabric and the fibres projecting from the threads of the fabric are glued down, but also the desired highly lustrous surface is gradually produced.

The brushes operate on the fabric only between each two guide-rollers 20 so that the contact between the brushes and the fabric is a resilient one, this securing the advantage of the bristles of the brushes penetrating also into the depths of depressions of the fabric. Thereby a lustrous condition is produced not only on the uppermost parts of the threads of the fabric, but also in the deeper parts of the surface.

Obviously the present invention is not limited to the illustrated embodiment as the same may be varied without departing from the spirit of the invention. For instance brush-rollers may be arranged also in such a manner that they operate on the upper surface of the fabric. If desired also heated rollers or heated pairs of rollers may be arranged between the successive brushes.

What I claim as my invention is:

1. A machine for manufacturing glacé fabric comprising a frame, a beam for winding off the fabric to be treated and a beam for winding up the treated fabric, a plurality of guiding rollers for the fabric arranged in staggered relationship between said beams, a trough adapted to contain a dressing substance, means for applying said substance to the fabric, and a plurality of successive rapidly driven rotating brushing-rollers arranged with their shafts transversely disposed with respect to the direction of movement of the fabric, said brushing-rollers being adapted to contact with said fabric between said guiding rollers.

2. A machine for manufacturing glacé fabric, comprising a frame, a beam for winding off the fabric to be treated and a beam for winding up the treated fabric, a plurality of guiding rollers for the fabric arranged in staggered relationship between said beams, said guiding rollers being arranged transversely of the direction of movement of the fabric and adapted to provide the fabric with a series of inclined portions, a trough adapted to contain a dressing substance, means for applying said substance to the fabric, and a plurality of successive rapidly driven brushing-rollers arranged with their shafts transversely disposed with respect to the direction of movement of the fabric, each of said brushing-rollers being arranged in the angle formed between two inclined portions of the fabric and adapted to contact

with the fabric at both of said inclined portions.

3. A method of manufacturing glacé fabrics as a substitute for known glacé fabrics manufactured of glacé threads, which comprises applying a coating of a suitable dressing to the surface of ordinary fabric and then subjecting the fabric while in a moist state to the intensive brushing action of a plurality of brushes all rapidly rotating in the same direction and in the direction of the warp of the fabric until the dressing has been distributed as a uniform coating on the exposed surfaces of the threads and in the interstices between the threads and all of the fibres projecting from the threads have been laid down against the threads themselves and the fabric has become lustrous throughout the concavities and convexities of its surface.

10 4. A method of manufacturing glacé fabrics as a substitute for known glacé fabrics manufactured of glacé threads, which comprises yieldably supporting ordinary fabric and applying a coating of a suitable dressing to the surface thereof, and subjecting the fabric directly after coating while still in a moist state to the intensive brushing action of a plurality of brushes all rapidly rotating in the same direction and in the direction of the warp of the fabric until the dressing has been distributed as a coating of uniform thickness on the exposed surfaces of the threads and in the interstices between the threads and all of the fibres projecting from the threads have been laid down against the threads themselves and the fabric has become lustrous throughout the concavities and convexities of its surface.

20 5. A method of manufacturing glacé fabrics as a substitute for known glacé fabrics manufactured of glacé threads, which comprises yieldably supporting ordinary fabric and applying a coating of a suitable dressing to the surface thereof, continuously moving the fabric in a resiliently supported position and subjecting it while still in a moist state to the intensive brushing action of a plurality of brushes all rotating in the same direction and in the direction of the warp of the fabric until the dressing has been distributed as a uniform coating on the exposed surfaces of the threads and in the interstices between the threads and all of the fibres projecting from the threads have been laid down in the same direction against the threads themselves and the fabric has become lustrous throughout the concavities and convexities of its surface.

30 6. A method of manufacturing glacé fabrics as a substitute for known glacé fabrics manufactured of glacé threads, which comprises yieldably supporting ordinary fabric and applying a contact coating of a suitable dressing to the surface thereof, continuously moving the fabric in a resiliently supported

position and subjecting it directly after coating and while still in a moist state to the intensive brushing action of a plurality of brushes all rapidly rotating in the same direction and in the direction of the warp of the fabric until the dressing has been distributed as a uniform coating on the exposed surfaces of the threads and in the interstices between the threads and all of the fibres projecting from the threads have been laid down against the threads themselves and the fabric has become lustrous throughout the concavities and convexities of its surface.

In testimony whereof I affix my signature.

FELIX WOLF.
